UNITED STATES PATENT OFFICE

2,525,976

COMBINED SPRING AND SNUBBER FOR
RAILWAY CAR TRUCKS

Richard G. Tillou, Lombard, Ill., assignor to W. H. Miner, Inc., Chicago, Ill., a corporation of Delaware

Application September 13, 1948, Serial No. 49,045

5 Claims. (Cl. 267—9)

1

This invention relates to improved combined spring and snubber for railway car trucks.

The main object of the invention is to provide a supporting spring for railway car trucks which has means for snubbing the action of the spring combined therewith and formed as an integral part of the same.

Other objects of the invention will more clearly appear from the description and claims hereinafter following.

In the accompanying drawings forming a part of this specification, Figure 1 is a top plan view of portions of the spring follower plate members of a truck spring cluster, illustrating my improved combined spring and snubber in connection therewith. Figure 2 is a vertical sectional view, corresponding substantially to the offset line 2—2 of Figure 1. Figure 3 is a horizontal sectional view, corresponding substantially to the line 3—3 of Figure 2. Figure 4 is a front elevational view of the improved combined spring and snubber shown in Figure 2. Figure 5 is a side elevational view of Figure 4, looking from right to left in said figure. Figure 6 is a view similar to Figure 4 showing the combined spring and snubber, as manufactured and before the friction elements thereof have been brought into assembled relation with each other. Figure 7 is a side elevational view of Figure 6, looking from right to left in said figure. Figure 8 is a view, similar to Figure 6, illustrating a step of the procedure of assembling the friction elements. Figure 9 is a view, similar to Figure 7, illustrating a further step of the procedure of assembling the friction elements.

Referring to the drawings, 10—10 indicate the top and bottom spring follower plates of a spring cluster of a railway car truck. These spring follower plates are of the usual design, with the exception that they are modified slightly, as hereinafter pointed out, to accommodate my improved combined spring and snubber.

The improved combined spring and snubber, as shown in the drawings, comprises broadly a coiled helical spring A having friction elements B—B formed integral therewith.

The spring A is in the form of a helical coil interposed between the top and bottom follower plates 10—10 of the spring cluster of a railway car truck. The spring A has the tangs at the upper and lower ends thereof, which tangs are indicated by 11—11, elongated and angularly bent away from the end coil to extend outwardly beyond the side of the spring, each extended tang having a horizontal section 12 substantially radial to the

axis of the spring proper, and a vertically disposed end section 13 at right angles to the horizontal section. The section 13 of the upper tang extends downwardly and that of the lower tang 5 extends upwardly. The outer end portions of the sections 13—13 are flattened to provide the friction elements B—B which are in the form of plates. The platelike friction elements B—B are in sliding contact with each other on their inner sides, which sides present flat friction surfaces 14—14. The spring A is coiled so that it exerts pressure to forcibly press the friction elements B—B against each other in the assembled condition of the same.

15 In manufacturing my improved combined spring and snubber, the procedure is preferably as follows: The spring A is coiled as shown in Figures 6 and 7, with the sections 13—13 of the upper and lower tangs bent respectively upwardly and downwardly, but reversely arranged in side by side relation with respect to their positions in the completely assembled condition of the device, that is, the depending section 13 of the top tang is at the left hand side of the upstanding section 13 of the bottom tang. As shown, the sections 13—13 are preferably also spaced laterally from each other. In assembling the friction elements B—B of the sections 13—13 with each other, the spring illustrated in Figures 6 and 7 is forcibly stretched lengthwise, as shown in Figure 8, to vertically separate the friction elements B—B so that the ends thereof will clear each other. While in this stretched condition, the top and bottom end portions of the spring are turned in reverse directions to swing the upper and lower friction elements B—B past each other, that is, the upper element to the right and the lower element to the left, as viewed in Figure 7, to position the upper friction element B to the 20 right of the lower element B so that the same will engage each other on their friction surfaces 14—14 when the spring is allowed to contract, as shown in Figure 9, and return to its normal contracted position, as shown in Figures 4 and 5. 25 As will be evident, in displacing the friction elements B—B from the positions shown in Figure 7 to their assembled condition shown in Figure 9, the spring A illustrated in Figures 6 and 7 is given a decided twist in uncoiling direction, thus placing the same under torsional strain whereby the torque of the same acts to forcibly press and hold the friction elements B—B in tight engagement with each other.

30 My improved combined spring and snubber is substituted for one or more of the coil spring

units of a cluster of truck springs, and in the present instance is illustrated as substituted for the central unit of a five unit cluster. The usual spring follower plates 10-10 of such a spring cluster are provided with flanges 15-15, as illustrated in the drawing, for centering the outer coil of the central spring unit. In carrying out my invention, one of these flanges of each spring follower plate is cut out, or notched, to accommodate the corresponding extended tang of the spring, as shown most clearly in Figure 3, the cut out or notched portion being indicated by 16.

The operation of my improved combined spring and snubber is as follows: Upon the spring cluster of a railway car truck being compressed between the top and bottom spring follower plates of the cluster, my combined spring and snubber, which is interposed between these follower plates, is compressed therewith. As the coil spring A of the device is compressed, the upper friction element B is moved downwardly with respect to the lower element B, sliding on the latter to provide the desired frictional resistance to snub the action of the truck springs. As the spring follower plates 10-10 are separated vertically during recoil of the truck springs, and during the recoil action of the spring A, the friction element B of the upper tang of the spring moves upwardly on the lower friction element B, thus snubbing the recoil action of the spring A.

I claim:

1. In a combined spring and snubber, the combination with a helically coiled spring member; of a pair of vertically disposed, cooperating friction elements in lengthwise sliding engagement with each other and formed integral with the coils at the upper and lower ends of said spring member.

2. In a combined spring and snubber, the combination with a helically coiled spring member;

of a pair of relatively vertically disposed, cooperating friction elements in lengthwise sliding engagement with each other and integral with the top and bottom tangs of said spring member.

3. In a combined spring and snubber, the combination with a helically coiled spring member; of a pair of relatively slidably, vertically disposed, cooperating friction elements formed integral with said spring member, each of said elements comprising an arm forming a continuation of the corresponding end coil of said spring member, and a friction plate member integral with said arm, said arm extending horizontally from said spring member to one side thereof, and each of said plates extending from the outer end of the corresponding arm at right angles thereto.

4. A helically coiled spring having the tangs at the upper and lower ends projecting outwardly beyond one side of the spring proper, said tangs having respectively downwardly and upwardly bent end portions in sliding frictional engagement with each other.

5. A helically coiled spring having tangs at the upper and lower ends having horizontal portions disposed substantially radially to the central vertical axis of the spring, and respectively depending and upstanding extensions on said horizontal portions in sliding frictional contact with each other.

30 RICHARD G. TILLOU.
